UNITED STATES PATENT-OFFICE.

GILBERT FOX ALLOM, OF LONDON, ENGLAND.

ELECTRIC-LIGHT REFLECTOR.

961,196.

Specification of Letters Patent. Patented June 14, 1910.

Application filed April 8, 1910. Serial No. 554,237.

To all whom it may concern:

Be it known that I, GILBERT FOX ALLOM, a subject of the King of Great Britain, residing at 15 George street, Hanover Square, 5 London, England, have invented new and useful Improvements in Electric-Light Reflectors, and of which the following is a specification.

My invention relates to reflectors for use 10 in connection with electric lamps, and to that class of reflector chiefly intended for illuminating pictures and tapestries and which is of channel shape and provided with tubular lamps which lie in the back of the 15 channel. When reflectors of this kind are used it frequently happens that a person standing to view a picture will, in looking at the upper part of the picture, either see the lamps, or the glare from the upper part 20 of the reflector, also an objectional glare is sometimes cast on to the top of the picture.

Now, the object of my invention is to provide means which will both obscure the 25 lamps and prevent a glare either to the eyes of an observer or upon the top of the picture without at the same time interfering with the illumination of such picture.

To this end my invention consists in arranging a screen or screens inside the reflector in such positions, that it or they will conceal the lamp and cover the glaring part 30 of the reflector in the manner hereinbefore described, the screens being mounted in the reflector in such a way that they can be arranged with their surfaces approximately 35 parallel to the rays which pass on both sides of them so that they obstruct only a minimum of light from the object to be illuminated.

40 My invention will be readily understood by reference to the accompanying drawing, in which:—

Figure 1 is a sectional side view of a lighting fitting carrying a reflector of the kind 45 in question and having two screens applied to it according to my invention and Fig. 2 is a view looking in the direction of the arrow, Fig. 1.

50 In these figures *a* indicates an ordinary channel shaped reflector, and *b*, *b* the lamps arranged therein, the said reflectors being

shaped in a well-known manner so that the rays will be reflected from it in more or less parallel lines.

c, *c*¹ are the screens which are arranged in accordance with my invention, at some distance from the surface of the reflector so that the light rays can pass behind them, the said screens being plain or non-reflecting metal strips attached at their ends to the reflector, for instance, by screws *d*, *d* which allow the said strips to be placed at any suitable angle.

With the described arrangement a person can stand beneath the reflector in a much more forward position, without seeing the lamp, than would be the case if the screen *c* was not employed, and the glare from the top of the reflector will be obscured by the screen *c*¹, which latter screen also prevents the upper part of the picture being unduly illuminated, but allows of the illumination being concentrated on the central portions of the picture or the like.

It will be understood that the width and 75 length of the screens *c*, *c*¹ can be varied according to the size of the reflector and the number of the lamps which the latter is intended to carry, also in some cases one of the screens can be dispensed with, or, if 80 desired more than two screens can be employed.

Claims.

1. In a lighting fixture, the combination with a channel-shaped reflector having a 85 tubular lamp or lamps fixed in the back of the channel, of a screen or screens having a plurality of non-reflecting surfaces and located in said channel.

2. The combination with a channel shaped reflector, having tubular lamps fixed in the back of the channel, of non-reflecting screens 90 adjustably secured to the end surface of the reflector, having flat surfaces and adapted to be placed in substantial parallelism with 95 the rays emitted from the lamps or from the reflectors.

GILBERT FOX ALLOM.
